UNITED STATES PATENT OFFICE

WILLIAM S. WESTON, OF DALLAS, TEXAS

ANTICREEPER FOR RAILWAY RAILS

Application filed January 12, 1929. Serial No. 332,176.

The present invention relates to improvements in spring clamp rail anchors or anti-creepers, and more particularly to rail anchors such as set forth in prior Letters Patent of the United States issued to me No. 1,572,455, dated February 9, 1926, and No. 1,646,512, dated October 25, 1927, and in which jaws are provided which are adapted, on installation, to establish a lever grip on the rail base flange.

The present invention seeks to provide a spring clamp rail anchor having at least two flange-embracing jaws which are so constructed as to give a greater range of adjustment to rail base flanges of different thickness. A further object of the invention is to provide improved means in a spring clamp rail anchor more particularly adapted to cooperate with a rail-seating tie-plate or the like, and in which improved means are provided for securing the anchor in position on the rail base.

With these and other objects in view, the invention consists in the features of improvement hereinafter set forth, illustrated in the preferred form in the accompanying drawings and more particularly pointed out in the appended claims.

In the drawings which illustrate the preferred form of the present invention that is adapted to cooperate with a rail-seating tie-plate:

Fig. 1 is a view in elevation of the anchor as seen in a cross section through the rail base and plate, taken on the line 1—1 of Fig. 3.

Fig. 2 is a side elevation of the rail base and anchor, as seen from the right of Fig. 1, the plate being omitted.

Fig. 3 is a plan view of the plate showing the anchor in its installed shape and position, the rail base being shown in dotted outline.

Fig. 4 is an elevation of the anchor only, taken from the same point of view as Fig. 2, showing its manufactured shape before it is sprung onto the rail base.

Fig. 5 is a plan view of the anchor in its manufactured shape. It may be noted here that to facilitate the comparison between

the manufactured and installed shape of the anchor, and the description of its installation, Fig. 5 is placed in front of the opening in the plate in Fig. 3.

Fig. 6 illustrates a blank for the anchor, before it is pressed and bent into shape, which may be punched from a stock bar of spring steel.

Fig. 7 is a cross section of the blank on the line 7—7 of Fig. 6, showing the jaw space punched at an angle inclined to the blank.

Referring to the drawings, the anchor is made with two flange-embracing jaws A and B that are integrally connected together at the inner ends of their top members by the loop L. The jaws are held in spaced relation to each other by this loop and by shoulders a and b formed on the top members at their outer ends. In the manufactured shape, as shown in Fig. 4, the jaws with the shoulders in contact are inclined toward each other in a downward direction. In this shape the flange-embracing spaces of the two jaws are oppositely inclined and so related that the clear space through both jaws is less than required for the rail base flange on which they are to be used. To illustrate this fact, the edge of the rail base and the outline of the jaw spaces adjacent the edge are indicated by dotted lines.

At installation when the anchor is driven onto the rail flange, causing the jaw spaces to adjust themselves to the base flange, as indicated in Fig. 2, the bottoms of the jaws are rotated away from each other. In this operation there is developed a torsional strain in the upper members of the jaws and a bending strain in the loop L. These strains, in their reaction, tend to rotate the jaws back to their manufactured relation and thereby establish and maintain the lever grip of the jaws on the base flange, a condition essential to the functional operation of the device. It is to be noted here that with the spring relation of the two jaws distributed through a torsional strain in the top members as well as a bending strain in the integral connection at loop L, the anchor is adaptable for application to rail bases of

varying thickness and for subsequent removal without a material distortion from its manufactured shape.

Referring to Fig. 2, the jaw spaces, as indicated by the dotted outline of these spaces adjacent the edge of the rail base, are larger than the thickness of the base. The effective grip in functional operation is therefore a lever grip with the bearing edges a^3 and a^4 paired in jaw A and bearing edges b^3 and b^4 paired in jaw B.

Because the jaw spaces are larger than the base flange, the same anchor is self adjusted to the slight variations of base thickness in rails of any standard section. In designing the anchor the spaces are preferably so proportioned that when mounted on the thinnest base it is to be used on the jaws will be rotated away from each other until substantially parallel, as shown in Fig. 2. This will give a substantially vertical plane contact between the bottom member of the jaw and the part of the substructure against which it bears when the rail begins to creep.

The anchor is adapted to be seated in a recess in a tie-plate or in the rail bearing plate of a metal tie. An important detail of my present improvement is means for the application and subsequent retention of the anchor on the rail after the rail with tie-plate have been installed. In Fig. 3 is illustrated a standard tie-plate T with the usual spike holes and with a shoulder t^2 on one side for one edge of the rail base. The opposite side of the plate is provided with a slot t that extends part way under the rail base and receives the bottom portion of the anchor as the latter is driven upon the rail base at installation. To illustrate this process, Fig. 5 showing the manufactured shape of the anchor is placed in line with the slot.

The free ends of the bottom members of the jaws are provided with flares or hooks a^5 and b^5 and these hooks are adapted to spring into side recesses t' at the inner end of the slot t when the jaws are rotated away from each other in the process of driving the anchor onto the rail to the position shown in Fig. 3. These hooks prevent the anchor from working off the rail in functional operation. To facilitate the installation, the outer end of the slot t may be flared, as indicated, to readily receive the hooks a^5 and b^5 when placed in contact by hand. The anchor is then driven by a hammer or spike maul in the direction indicated by arrow 2 in Fig. 5 to the final position of Fig. 3.

In the process of installation just described, during which, momentarily, the free ends of the bottom members are held at substantially their manufactured distance from each other by the sides of the slot t , a bending strain is developed in the lower

jaw members which opposes the spread of the jaws from their manufactured position. Some of this strain may be retained after installation and to that extent is auxiliary to the strains in the upper members for maintaining the lever grip of the jaws as previously described.

As the rail, viewed in Fig. 3, tends to creep the bottom member of one of the jaws is brought to a bearing against the edge of the slot t and the reaction of the substructure through this bearing utilizes the lever grip of the jaws to prevent further creeping. A reliable bearing between the anchor and the edge of the slot in the plate is therefore important. To insure the maintenance of this bearing during the slight vertical movement of the rail relative to the plate, caused by the wave movement of the rail under passing loads, I extend a portion of the bottom member of each jaw below the bottom of the plate T in which the slot t is made. These extensions a' and b' are preferably made below that portion of the anchor connecting the top and bottom members of the jaws. These extensions facilitate making the connections between the upper and lower jaw members that extend around the edge of the rail base, wider and more unyielding, so that the angle between the upper and lower jaw members adjacent their connection around the edge of the rail base is not materially affected by the distortions of installation or in functional operation. The extensions will also necessarily cut into the wooden tie to which the tie plate is spiked, but this will not affect the grip of the anchor on the rail or its operation.

The improved anchor can be economically manufactured from relatively thin, flat bars of spring steel, sections of which can be cut off and punched into the forms shown in Figs. 6 and 7. This blank which is of substantially uniform thickness is bent about its central transverse portion to bring the jaws A and B side by side and form the intermediate U-shaped portion or loop L. Shoulders a and b at the outer ends of the upper jaw members and the hooks a^5 and b^5 at the inner ends of the lower jaw members are readily formed by offsetting and shaping these parts. It is noted that the opening in the blank shown in Figs. 6 and 7, which forms the spaces between the upper and lower jaw members, is punched at a slight incline or angle, so that the edges of the jaw openings are oppositely inclined to the side faces thereof as described and as shown in Figs. 2 and 4. In operative position, the relatively thin, flat jaws are disposed on edge upon the rail base flange and the metal is so disposed that it is well adapted to withstand the strains brought upon the anchor at installation and in operation.

Throughout the specification and claims, the term "jaw" has been used to designate an element having integrally connected members adapted to embrace one of the rail base flanges.

5 Obviously, changes may be made in the details of construction without changing the novel features of improvement, as set forth in the appended claims.

10 I claim as my invention:

1. A spring clamp rail anchor adapted to be strained on installation and having a part arranged to snap into engagement with a part of the substructure to retain the anchor 15 in position on the rail base.

2. A spring clamp rail anchor comprising a flange-embracing jaw, the lower jaw member having a hook, and a rail seating part having a recess for receiving the lower jaw 20 member and a notch into which said hook is sprung on installation to hold the anchor in position on the rail.

3. A spring clamp rail anchor comprising connected flange-embracing jaws adapted on 25 installation to establish and maintain lever grips on one of the rail base flanges, the lower jaw members having hooks, and a rail seating part or plate having a recess for receiving the lower jaw members and forming abutments therefor to resist creeping of the rail and also having notches into which said hooks are sprung to retain the anchor against displacement.

4. A spring clamp rail anchor comprising 35 two flange-embracing jaws adapted on installation to establish lever grips on one of the rail base flanges, and a rail seating part or plate having a recess for receiving the lower jaw members and cooperating there- 40 with to resist creeping of the rail in either direction, the upper jaw members being spaced apart throughout the greater portion of their length and having a connection at their inner ends arranged to develop a torsional strain at installation in the upper jaw 45 members to aid in maintaining the lever grips of the jaws.

5. A spring clamp rail anchor comprising a flange-embracing jaw, and a rail seating 50 plate having a recess for receiving the lower jaw member and forming an abutment therefor, said lower jaw member being arranged to extend below the plate to maintain engagement therewith during relative vertical 55 movement of the rail.

6. A spring clamp rail anchor comprising two flange-embracing jaws having substantially rigid connections between their upper and lower jaw members and an integral con- 60 necting loop between the inner ends of the upper jaw members, said jaws and loop being formed of a bent, relatively thin, flat metal blank and adapted to be disposed on edge and strained on installation to estab- 65 lish lever grips on one of the rail base

flanges, the upper jaw members being spaced apart throughout the greater portion of their lengths and having abutting portions adjacent their outer ends.

7. A rail anchor comprising a flange-embracing jaw and a rail-seating part, the lower jaw member and said rail-seating part having interlocking shoulders for holding the jaw against movement transversely of the rail.

8. A rail anchor comprising a flange-embracing jaw and a rail-seating part having a shoulder, the lower jaw member having a hook adapted on installation to snap into engagement with the shoulder of the rail-seating part to hold the jaw member in position on the rail.

9. A spring-clamp rail anchor comprising two flange-embracing jaws adapted on installation to establish lever grips on one of the rail base flanges, and a rail-seating part or plate having a recess for receiving the lower jaw members and cooperating therewith to resist creeping of the rail in either direction, the upper jaw members having a connection at their inner ends arranged to develop torsional strain in the upper jaw members to aid in maintaining the lever grips of the jaws.

10. A spring-clamp rail anchor comprising two flange-embracing jaws having an integral connecting loop between the inner ends of the upper jaw members and a substantially rigid connection between the upper and lower members of each jaw, said jaws and loop being formed of a relatively thin, flat metal blank adapted to be disposed on edge and strained on installation to establish lever grips of the jaws on one of the rail base flanges, and at least one of the lower jaw members having means for holding the anchor in position on the rail.
